UNITED STATES PATENT OFFICE.

MARTIN MOLONY, OF SAN FRANCISCO, CALIFORNIA.

HIGH-FREQUENCY VESICAL ELECTRODE.

Application filed January 2, 1926. Serial No. 79,366.

This invention relates to surgical instruments and particularly to that class known as high-frequency vesical electrodes. An object of the invention is to provide a simple 5 compact device in catheter form to be inserted into an internal body cavity through a natural opening. A further object is to provide the electrode with an adjustable beak or tip and positive though simple means under control of the operator to manipulate the same. Further objects are to provide an instrument of this class which will not only be effectively insulated electrically but which at the same time is readily cleansed and 10 made sterile, and yet which while of light weight is not subject to deterioration and chemical decomposition.

The high frequency electrode of this invention is intended to be used primarily in 20 combination with a cystoscope introduced through a supra pubic cystotomy opening, the latter for the purpose of observing and directing the action of the electrode during diathermic fulguration. The electrode of 25 this invention is used trans-urethrally for the surgical treatment of obstructions and deformities at the neck of the bladder, and for growths in its interior.

In the drawings—

30 Fig. 1 shows the manner of using the instrument for removing a growth at the vesical orifice.

Fig. 2 is a detail showing the instrument destroying an intravesical growth.

35 Fig. 3 is a view of the complete instrument.

Fig. 4 is a sectional view of the sheath.

Fig. 5 is a view of the electrode parts with 40 the sheath removed and the head and handle portions in section.

Fig. 6 is a detailed view of the head showing the manner of adjustment.

Fig. 7 is an enlarged detailed view showing the construction at the tip or beak, and

45 Fig. 8 is a second detailed view of the tip.

In the embodiment of my invention shown in the drawings A is a cylindrical tube of insulating material preferably "bakelite" or similar phenol condensation product. This 50 tube or sheath is of an external diameter approximating the minimum average internal surgical diameter of the duct in which it is to be inserted, for example, the urethra, and of a length between distal end and head 55 B equal to the maximum length of the parts in which it is to be inserted. The head B

is formed of the same material as the sheath, A, as is also the tubular extension C. These parts are all securely and rigidly secured together as by moulding or otherwise so as to 60 form an integral whole.

The electrode proper comprises a metal tip 1 screwed to a metal member 2. The part 2 is pivotally connected to each of two long thin metal rods 3 and 4. Of the rods 65 3 and 4, the one designated 3 is securely and rigidly held in a head D of "bakelite" or similar insulating material, while the other rod 4 passes freely through D and is in its turn secured rigidly to terminal E. Terminal 70 E is also of "bakelite" or similar substance. The part C on head B fits into the axially arranged socket S on head D. The pivot point 5 of rod 3 in member 2 is slightly in 75 advance of the pivot point 6 of rod 4 in member 2. The outer ends of the rods 3 and 4 are flattened and are accommodated in a slot 7 in member 2.

By means of the construction first described the tip or beak of the electrode is 80 in axial position when the parts D and E are slightly separated, but on member E being moved toward D the rod 4 will also be moved axially and will cause the beak 1 to rotate about the relatively stationary point 85 5.

To assure smooth operation in the relative movement of parts D and E, the member E is provided with an axially arranged projection F which fits into a second axially 90 arranged socket S' in head D. The beak or tip is fixed and limited in its various angular positions by means of a set screw 10 screwed through terminal E and bearing at 95 its end against the head D. A pin 11 extending from head D on one side thereof cooperating with a hole in head B prevents relative rotation of these parts, while a similar pin 12 on the other side of D cooperating 100 with a hole in E likewise performs this function for these two parts.

The radially arranged connector for leading the high frequency current is shown at 20 and consists of an insulating cylinder of "bakelite" or similar material inserted in head E. Within this cylinder is a metal spring split-clip arrangement 21 connected to rod 4 so that as one side of the source of high frequency current is connected to clip 21 the current will be also connected 110 to the electrode tip 1.

In Fig. 1 there is shown a manner of using

the instrument for fulguration of obstructions at the vesical orifice. Here V is the cystoscope inserted through the supra-pubic cystotomy opening. By inserting the cystoscope through the sinus as shown, the action of the electrode can be definitely and accurately observed and directed.

The active electrode is connected to one side of a high frequency source of current 10 as indicated at M and the other side of the source is connected to the indifferent electrode N bearing against the back of the patient.

What I claim is:

15. 1. A vesical electrode for high frequency current comprising the combination of a fixed rod, a second rod movable relative thereto, a terminal beak pivotally attached to both of said rods, and means for moving 20 the one rod relative to the other to angularly swing said beak.
2. A vesical electrode for high frequency current comprising the combination of a fixed rod, a second rod axially movable relative thereto, a terminal beak pivotally attached to both of said rods, and means for moving the one rod relative to the other to angularly swing said beak.
3. A vesical electrode for high frequency 30 current comprising the combination of a sheath, a rod in the sheath and fixed therein, a cauterity tip mounted on the rod, a second rod in the sheath movable relatively to the first rod and attached to the tip, and means for moving the second rod.
4. A vesical electrode for high frequency current comprising the combination of a fixed rod, a second rod movable relative thereto, a terminal beak pivotally attached to both 40 of said rods, means for moving the one rod relative to the other to angularly swing said beak, and means to fix the beak in angular position.
5. A vesical electrode for high frequency 45 current comprising the combination of a sheath, a rod in the sheath and fixed therein, a cauterity tip swingably mounted on the rod, a second rod in the sheath movable relatively to the first rod and attached to the 50 tip, and means for moving the second rod.

6. A vesical electrode for high frequency current comprising the combination of a sheath, a rod in the sheath and fixed therein, a cauterity tip swingably mounted on the rod, a second rod in the sheath movable 55 relatively to the first rod and attached to the tip, means for moving the second rod, and means to fix the tip in angular position.

7. A vesical electrode for high frequency current, comprising an elongated member 60 of insulating material rigid throughout the greater part of its length and having a swingable metallic cauterity tip.

8. A vesical electrode for high frequency current, comprising an elongated member of 65 insulating material rigid throughout the greater part of its length and having a swingable metallic cauterity tip, pivotally connected to the member.

9. A vesical electrode for high frequency 70 current, comprising an elongated sheath of insulating material, a metallic rod in the sheath and fixed therein, a cauterity tip pivotally connected on the rod, a second rod in the sheath movable relatively to the first 75 rod and pivotally connected to the tip, means for moving the second rod, and means for connecting a source of high frequency current to the first rod.

10. A vesical electrode for high frequency 80 current; comprising an elongated sheath of insulating material; a metallic rod in the sheath and fixed therein; a smooth, tapered, blunt-nosed, metallic, cylindrical, cauterity tip swingably connected at one side of its rear end to the rod; a longitudinally movable second rod in the sheath having a pivotal connection with said tip at the rear end thereof laterally at a distance from the swingable connection; means for moving 90 said second rod; means for fixing the longitudinal movement of the second rod relative to the first rod and so the angular position of the tip; and means for connecting a source of high frequency current to the 95 first rod.

In testimony whereof I have signed my name to this specification.

MARTIN MOLONY.
